UNITED STATES PATENT OFFICE.

BIRGER OTTAR HOLM-HANSEN, OF CHRISTIANIA, NORWAY.

ELECTRIC GOVERNOR.

1,263,413.

Specification of Letters Patent. Patented Apr. 23, 1918.

Application filed August 9, 1915. Serial No. 44,475.

To all whom it may concern:

Be it known that I, BIRGER OTTAR HOLM-HANSEN, a subject of the King of Norway, residing at Christiania, Norway, have invented certain new and useful Improvements in Electric Governors; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to an apparatus for automatic regulation as well in continuous current as in alternate current electric plants.

The object of the invention is to provide 20 an automatic governor, in which variations in the circuit to be controlled directly or indirectly produce variations in a magnetic field, whereby in accordance with these variations electric circuits are closed and opened, 25 which automatically effect adjustment of the potential or current in question to the desired value.

A further object is to provide means to so 30 control the tension that the same is caused to vary in a desired manner, when the consumption current is altered.

The invention comprises the parts herein-after described and their construction, and combination such as illustrated in the annexed drawing, which shows an embodiment 35 of the invention.

Figures 1 and 2 show diagrammatically the part of the governor which contains the variable magnetic current and the electric 40 contact devices operated by same.

Fig. 3 shows the means for operating the usual regulator arm or the like by means of devices actuated by the electric currents closed by the said electric contact devices.

Fig. 4 shows an embodiment of a diagram of connections for the automatic tension governor coupled upon a plant for triphase high tension alternating current.

In Fig. 1 the iron core 1 which is provided 50 with a tension coil is fed directly or indirectly with current from the electric source of energy whose tension is to be controlled. Movable in a recess in the iron is the armature 3 whose position is controlled by the 55 spring 4 and the attraction produced between the core and the armature by the elec-

tric current flowing through the tension coil 2.

To the armature 3 is secured a lever 5 sliding on contact paths 6 and 7. One of the latter is sectioned in two parts insulated from each other by an insulating piece 18 so that the current will be interrupted when said arm 5, which is provided with a sliding contact connecting the contact paths 6 and 7 with each other, has passed this insulated point.

The contact paths are secured to and insulated from a support 8 carried by a lever 25 which is mechanically connected with an armature 9 movable in a recess in the iron core 10. This iron core is surrounded by a current coil 11 connected directly or indirectly with the electric source of energy whose tension is to be controlled. Both of the cores, 1 and 2, are laminated, hollow rectangles, one corner being cut away to receive the respective laminated, spring-retracted, sector-shaped armatures, 3 and 9. This arrangement permits a constant magnetic resistance through an air gap of constant width between the horizontal hub of the core and the armature, and a variable magnetic resistance through a variable air gap between the vertical limb of the core and the armature.

The position of the armature 9 is controlled by a spring similar to the spring 4 and by the attraction produced between the core and the armature by the electric current passing through the current coil 11.

The above device which is designed to be assembled into one apparatus and inclosed in a casing, forms the tension governor proper which operates the cutting in of the electric clutches shown in Fig. 3.

To the device controlling either directly or indirectly the main tension of the plant is secured a shaft 13. When this shaft is moved to and fro the tension will increase or decrease. This motion is transmitted from a small working motor 14 through a worm gear 24 by means of an electric coupling comprising a driving gear 15 which actuates the conical gears 16 and 17. To these gears 105 are secured respectively electromagnets 21 and 22 fed through the sliding rings 19. These magnets are loose with their wheels on the shaft 13 and on the latter is keyed an armature 23.

The small driving motor 14 is here designed to be connected with the tension of

the magnetizing machine 36 from which the electric clutches are likewise fed. The magnetizing machine has a field winding 39.

The mode of operation of the above apparatus is as follows:

When the generator 37, having a field winding 40, has been brought up to normal working speed and approximately normal tension of the machine has been attained, the 10 working motor 14 is cut in. The same will then rotate and carry along the loose gears 16 and 17. If the tension of the generator is now insufficient the lever 5 which is secured to the armature 3 (Fig. 1) will take 15 such a position on the contact paths 6 and 7 as to cut in the electric magnet 21, whereby the armature of the latter will be attracted and the working motion of the motor transmitted through this coupling to the governing 20 apparatus whereby the tension is increased. When the tension has attained the proper amount the lever 5 will take such a position on the contact path as to interrupt the current owing to its making contact with 25 the insulating piece 18. The electromagnet 21 will therefore cease to attract its armature and the latter will stop whereby the shaft 13 will cease to rotate and the contact lever will receive no motion from the shunt 30 regulator and the tension will consequently remain constant. If the tension should increase beyond the normal value, the electric clutch 22 will in like manner be cut in and remain connected until the proper tension 35 has been attained. The tension coil 2 is here designed to be connected to a tension transformer 41.

If the tension is not only to be kept constant but also to be regulated according to 40 the consumption current there may be cut in a current transformer 38 (Fig. 4) to feed the current coil 11. When the current increases, the armature 9 will move in such a manner that the support 8 of the contact 45 path will be displaced upwardly, thereby increasing the tension of the generators in

order to enable the lever 5 to take its neutral position on the insulating piece.

The above invention may be used as tension governor, as current governor or as a 50 governor controlling in accordance both with current and with tension.

I claim—

1. In apparatus of the character described, a pair of adjacent electromagnets each comprising a winding, a core whose poles are at an angle to one another and have arcuate faces, a yieldingly supported armature having an arcuate face for coöperation with said pole faces and pivoted with relation to said poles to maintain an air gap of constant width with respect to one of said poles and an air gap of variable width with respect to the other pole, and a circuit closing member carried by the armature, the circuit closing member of one of said armatures being proximate to and coöperating with the member of the other armature. 55

2. In apparatus of the character described, a pair of adjacent electromagnets each comprising a winding, a core whose poles are at an angle to one another and having arcuate faces, a yieldingly supported armature having an arcuate face for coöperation with said pole faces and pivoted with relation to said poles to maintain an air gap of constant width with respect to one of said poles and an air gap of variable width with respect to the other pole, and a circuit closing member carried by the armature, the circuit closing member of one of said armatures being proximate to and coöperating with the member of the other armature, one of said magnets being responsive to variations of voltage and the other responsive to variations of current. 75 80 85

In testimony that I claim the foregoing as my invention, I have signed my name in presence of two subscribing witnesses.

BIRGER OTTAR HOLM-HANSEN.
